Primary Examiner — Garth Rademaker*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side rear perspective view thereof;

FIG. 5 is an opposite side view thereof;

FIG. 6 is an opposite side front perspective view thereof;

FIG. 7 is a front view thereof; and,

FIG. 8 is a top view thereof.

The broken line immediately adjacent to the shaded area defines the bound of the claimed design and form no part thereof. The broken lines depicting the remainder of the shoe form no part of the claimed design.

1 Claim, 8 Drawing Sheets(56)
